(57) **CLAIM**

The ornamental design for a reservoir assembly, as shown and described.

DESCRIPTION

FIG. 1 is a perspective view of the reservoir assembly according to the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depicting certain top surface features shown in FIGS. 1, 2, 3, and 6 are for illustrative purposes and form no part of the claimed design.

1 Claim, 5 Drawing Sheets

FIG. 1

FIG. 2

FIG. 3

FIG. 4

FIG. 5

FIG. 6**FIG. 7**
